SEAT BELT BUCKLE

Robert E. Meshew, Birmingham, Mich., assignor to
General Motors Corporation, Detroit, Mich., a
corporation of Delaware

Filed Feb. 25, 1966, Ser. No. 530,043
4 Claims. (Cl. 24—230)

ABSTRACT OF THE DISCLOSURE

In a seat belt assembly, a lock plate is attached to one of the strap ends and is engageable with a buckle which is adjustably attached to the other strap end. The buckle comprises a frame which mounts a strap adjustment slide bar that is enclosed by a rear cover. The frame includes channel-shaped sides and a locking boss struck out from the base and engageable with the lock plate. A spring is secured to the base and includes a pair of curved arms confined in the side channels for biasing the inserted lock plate downwardly into engagement with the locking boss. A front cover engages the spring and is confined within the side channels. The front cover includes a pair of depending curved tabs which rockably engage the base and underlie the inserted locking plate. Lifting causes pivoting or rocking of the cover member on the tabs which raise the lock plate against the bias of the spring arms and out of engagement with the locking boss to permit withdrawal.

This invention relates to buckle mechanisms, and more particularly it relates to a seat belt buckle which is adapted to cooperate with a latch plate to secure a body within the confines of the seat belt.

It should be clear that the subject buckle will have many different uses such as the preferred embodiment wherein the buckle is attached to one length of belt and engages a cooperating lock plate which is fastened to another length of belt. This general type of buckle and lock plate assembly has common widespread use in automobiles for securing passengers within a vehicle seat. With this widespread use of buckles in seat belt assemblies there is a need for a relatively simple and economical buckle which will effectively engage a lock plate.

It is, therefore, an object of this invention to provide a relatively simple buckle which requires only its frame member to be of a strong material as the remainder of the component parts are not subjected to the loads on the seat belt assembly.

Other objects, features, and advantages of this invention will become obvious upon reference to the following detailed description and the drawings depicting the preferred embodiment thereof, wherein:

FIGURE 1 is a plan view with parts broken away and in section;

FIGURE 2 is a sectional view taken in the plane of line 2—2 in FIGURE 1 showing the buckle and lock plate in the engaged position;

FIGURE 3 is the same sectional view as FIGURE 2 showing the buckle and lock plate in the disengaged position;

FIGURE 4 is a cross sectional view taken in the plane of line 4—4 in FIGURE 1; and

FIGURE 5 is a perspective exploded view of the component parts of the buckle assembly.

FIGURE 1 shows a buckle 10 attached to one segment of a belt 12 engaging a lock plate 14 which also is attached to a belt 16. It should be noted that the belts 12 and 16 may be separate lengths of belt as attached to fixed anchors at their opposite ends such as in a seat belt assembly or they may be the opposite ends of the same

length of belt. The lock plate 14 may be any suitable plate-like structure having an aperture 18 therethrough forming a lock engaging shoulder 20, or other equivalent lock-engaging structure.

5 The main structural element of the buckle 12 is a substantially channel-shaped frame 22 which has a base 24 and a pair of sides 26 with inturned flanges 28. The base 24 of the frame 22 has a large rectangular aperture 30 formed therethrough to receive the belt 12. The belt 12 is adjustably looped around a rectangular slide bar 32. The slide bar 32 fits between U-shaped ribs 34 and 36 which are secured relative to each other by means of a slide bar adjuster plate 38 and positioned within the frame 22 under the inturned flanges 28. This slide bar adjuster plate 38 is slidable within the frame 22 to thereby allow movement of the belt 12 around the slide bar 32 thereby allowing adjustment of the length of the belt 12. The slide bar adjuster plate 38 further includes a U-shaped end rib 40 which closes one end of the frame 22.

10 The frame 22 has formed from its base 24 a locking boss or pawl 42 having a substantially transverse locking edge 44. This boss 42 is adapted to extend through the aperture 18 in the lock plate 14 so that the transverse locking edge 44 abuts the retaining surface 20 in the aperture 18 thereby fastening the lock plate 14 to the buckle frame 22. It should be noted that the buckle frame 22 carries all of the load transmitted through the buckle assembly by way of the belts and thus is the only portion of the buckle assembly 12 which requires a high degree 15 of structural integrity.

15 A cover 46 includes a decorative and relatively planar upper surface 48 and offset rear portion 50 with slots 52 cut therethrough and a pair of arms 54 bent inwardly from the sides of the portion 50. A pair of slits 56 are cut 20 into the cover 46 thereby providing openings for the inturned flanges 28 on the frame 22 so that the cover 46 can be slid into engagement with the frame 22 so that the upper decorative portion 48 is on top of the inturned flanges 28 and the rear portion 50 and the inturned arms 54 are positioned within the frame 22 underneath the inturned flanges 28. As best seen in the dashed lines in FIGURE 1, the inturned arms 54 also extend away from the lower portion 50 so that in assembly with the frame 22 they underlie the latch plate 14 when it is in locking relation with the pawl 42. A spring member 60 is positioned 25 within the frame so that its upturned feet 62 extend into the slots 52 in the lower portion 50 of the cover 46 thereby fastening the spring 60 to the cover 46. The spring 60 further has a slot 64 cut therethrough and a tab 66 which 30 are adapted to cooperate with lanced portions 68 in the base 24 of the frame 22 so that the tab 66 is positioned between the lanced portions 68 thereby fixing the spring 60 relative to the frame 22. The spring member 60 also 35 has a pair of spring arms 70 which extend forwardly underneath the inturned flanges 28 and overlie the lock plate 14 when it is positioned over the boss 42. The spring arms 70 thereby bias the lock plate 14 into locking engagement with the boss 42.

40 When release of the lock plate 14 from the buckle 12 is desired, the cover 46 is lifted slightly, as shown in FIGURE 3, thereby causing the arms 54 to raise and disengage the lock plate 14 from the boss 42 where it is free to be withdrawn from the buckle. Thus, the cover 46 serves both as a decorative cover and as a single piece 45 release mechanism for disengaging the lock plate from the buckle. Hence, the cover 46 can be constructed from any suitable light weight metal as it does not withstand any of the loads existing in the belt assembly. Thus, this invention provides a relatively simple and economical 50 buckle which can be used in combination with a standard lock plate to secure two belt members together. This

buckle has very few parts and therefore will be economical and easy to assemble. This buckle also provides a lock plate release mechanism which is incorporated with the decorative cover into one single unit. Thus, a buckle assembly has been provided which solves the problems of high cost and complexity associated with the many varieties of buckle assemblies now used in automobiles in conjunction with safety seat belts.

Although but one embodiment of this invention has been shown and described in detail, it should be clear to those skilled in the art to which the invention pertains that many changes and modifications may be made there-
10 to without departing from the scope of the invention.

I claim:

1. In combination with a pair of strap ends, a buckle attached to one of the strap ends and including a frame member having a locking boss formed integrally with the base thereof, and a lock plate attached to the other strap end and insertable within the buckle into engagement with the locking boss to interengage the buckle and lock plate, the improvement comprising a spring member mounted on the frame member and having means engaging the lock plate upon insertion of the lock plate within the buckle to bias the lock plate into engagement with the locking boss, a cover member attached to the spring member and pivotally mounted within the frame member in overlying relation to the spring member and locking boss, and tab means formed integrally with the cover member and underlying the inserted lock plate, the cover member causing the tab means to lift the lock plate against the spring bias and out of engagement with the locking boss to enable withdrawal of the lock plate from the buckle.
15

2. The combination of claim 1, wherein the frame

member includes side channel portions and the spring member engaging means includes a pair of curved arms confined within the channel portions, the curved arms being compressible within the channel portions by the lock plate upon insertion.
5

3. The combination of claim 2, wherein the cover member tab means include a pair of depending curved tabs confined within the side channels and engaging the frame base to enable pivotal movement of the cover member, the tabs including portions underlying the inserted lock plate.
10

4. The combination of claim 3, wherein the buckle member includes a pair of lanced tabs and the spring member includes a portion confined therebetween to locate the spring member longitudinally of the frame member, the spring member including a pair of projections and the cover member including a pair of slots receiving the projections to locate the cover member longitudinally of the spring member and the frame member.
